REFRIGERATOR

Montgomery Ferar, Huntington Woods, Mich., assignor
to Whirlpool-Seeger Corporation, St. Joseph, Mich., a
corporation of Delaware

Application September 11, 1956, Serial No. 42,900

Term of patent 7 years

(Cl. D67—3)

Fig. 1

Fig. 2

Fig. 1 is a front perspective of a refrigerator embodying my new design, the refrigerator being illustrated open and with the vertical shelf unit in extended position.

Fig. 2 is an enlarged fragmentary plan view of the decorative detail indicated in Fig. 1, it being understood that this decorative detail covers the entire paneled area of the shelf unit.

The dominant features of the design reside in the portions shown in full lines.

I claim:

The ornamental design for a refrigerator, as shown and described.
